UNITED STATES PATENT OFFICE.

FREDERICK G. FARR, OF NEW YORK, N. Y.

HYDRAULIC OIL-DELIVERY SYSTEM.

Application filed May 22, 1922. Serial No. 562,914.

The invention relates to hydraulic oil storage and delivery systems and more particularly to systems designed for use in connection with oil burning furnaces for the supplying of fuel to the same. With such systems it is usual to arrange the storage tank outside of the building and generally buried in the ground, while the oil is fed from said tank by water displacement through a conduit leading to the burner. The control of the feed is through a valve for the displacement liquid and this in turn is usually controlled by electro-magnetic means thermostatically or otherwise controlled. Therefore, whenever the valve is opened, oil will be displaced from the storage tank and fed through the delivery conduit.

It sometimes happens that an oil delivery pipe may spring a leak and in such event there is nothing to prevent the continuous delivery of oil through the leak, flooding the basement, with danger of explosion. To guard against such a result I have devised a system where the oil delivery conduit is completely encased in the water supply conduit. This not only affords protection for the oil conduit, but also in case of accident by which the conduits are broken, the water pressure would be released so that no oil could be delivered.

My invention also comprises other features of improvement as more fully herein-after set forth.

35 In the drawings:

The figure illustrates my improved system diagrammatically in vertical section.

A is the wall of the building which encloses the basement B, and C is the storage tank which is outside of the building and buried in the ground. D is the filler for the storage tank, also outside the building, and E is a tell-tale or indicator for showing when the tank is completely filled, these parts being similar in construction to devices heretofore used.

The delivery conduit F for the oil to the burner is preferably connected to the filler conduit D' and extends through the wall A into the basement to the burner. Surrounding this delivery conduit F is a water con-

duit G, which preferably extends the full length thereof and which is connected at one end to the downwardly extending water conduit H leading to the storage tank. This 55 water conduit H is also connected to the water supply I controlled by a valve J which, if desired, may be electrically controlled as indicated at K. The arrangement is such that the water which is admitted 60 through the valve J will pass between the inner oil conduit F and the surrounding water conduit G through the water conduit H and thence downward into the tank C to effect the displacement of the oil. The oil 65 will then pass outward through the conduit F to the burner, but in case of any leakage in the oil conduit F, the oil escaping will still be retained by the water conduit G. It is also evident that any accident which 70 might break the conduits F and G would, by releasing the water pressure, prevent the feeding of any oil outwardly through the oil conduit F to the burner converted at extreme left end of oil feed pipe F, and thus 75 avoid fire hazards.

To simplify the installation the water conduit H is preferably aligned with the oil filler conduit D' and is connected thereto by a fitting L having a partition for separating 80 the water in pipe G—H from the oil in pipe D' through which the oil delivery conduit F passes. This completes the water enclosure of the oil delivery conduit F to the point of connection with the oil supply tank C. The 85 conduit F preferably extends upward beyond the fitting L in the oil filler D' to a point above the hydrostatic head of the water, so that it will be impossible for water to be forced in the oil line.

90 While the enclosing water conduit G—H will prevent escape of oil from the delivery conduit F, even where the latter is leaking, it is desirable to detect the presence of oil which may have leaked into the water conduit. This is accomplished by a riser water pipe M within the basement and having a transparent observation chamber N at the top thereof into which any escaping oil will 95 be forced by the water displacement. The 100 drain through which the water is displaced when the tank C is being filled is arranged

within the basement and rises to a point system, the combination with an external oil storage tank, of regulated means for feeding displacement water located within a building, a water conduit extending from said regulated feeding means through the 70 wall of the building and to said external tank, an oil delivery conduit housed within said water conduit, a drain connection for said water conduit extending to a point above the normal hydrostatic head and 75 through which the water is displaced upon the filling of the tank with oil, and a riser from said water conduit in advance of said drain connection having a transparent portion above the normal hydrostatic head of 80 the water in which the presence of oil in said conduit will be detected.

5. In a hydraulic oil storage and delivery system, the combination with a storage tank, of an oil delivery conduit and means extending it from said tank, a water conduit also connected to said tank and arranged to surround a portion of said oil delivery conduit, means for supplying displacement water to 85 said water conduit, a riser extending from said water conduit and arranged to collect 90 therein any oil leaking from the oil delivery conduit into the displacement water conduit, and means for indicating the presence of the oil collected in said riser.

10. into the transparent chamber instead of passing over into the sewer.

It is now seen that the oil feed pipe F to a burner is entirely concealed in the water pipe G and this makes for safety.

15. The plug partition in the pipe fitting L diverts the oil, while filling, into the tank C, and also directs water from pipe H to G for wasting through waste pipe O-P and for carrying oil up into sight chamber N.

What I claim as my invention is:

1. In a hydraulic oil storage and delivery system, the combination with a storage tank and an oil filler conduit therefor, of a water displacement conduit, a fitting mechanically 25 connecting said conduits and having a portion separating the two conduits, and an oil delivery conduit enclosed within said displacement water conduit and passing through the separating portion of said fitting into communication with said oil filler conduit.

2. In a hydraulic oil storage and delivery system, the combination with a storage tank, of an oil filler conduit therefor having a 35 vertical portion, a conduit for displacement water having a vertical portion aligned with the vertical portion of said filler conduit, mechanically connected thereto, communicating with a laterally extending portion, 40 separating means disposed between the oil filler and water conduits, and an oil delivery conduit housed within the laterally-extending portion with said displacement water conduit, communicating with said oil filler conduit and extending upward therein to a 45 point above the hydrostatic head of the displacement water.

3. In a hydraulic oil storage and delivery system, the combination with a storage tank, of an oil filler conduit connected thereto, a conduit for the displacement water having a portion aligned with said oil filler conduit, a fitting for said oil filler and displacement water conduits having a partition 55 separating the two conduits, a laterally-extending conduit for the displacement water connecting with the water compartment of said fitting and an oil delivery conduit housed within said laterally-extending conduit for the displacement water, said oil delivery conduit passing through said partition and upward in said filler conduit to a point above the hydrostatic head of the displacement water.

4. In a hydraulic oil storage and delivery

system, the combination with an external oil storage tank, of regulated means for feeding displacement water located within a building, a water conduit extending from said regulated feeding means through the 70 wall of the building and to said external tank, an oil delivery conduit housed within said water conduit, a drain connection for said water conduit extending to a point above the normal hydrostatic head and 75 through which the water is displaced upon the filling of the tank with oil, and a riser from said water conduit in advance of said drain connection having a transparent portion above the normal hydrostatic head of 80 the water in which the presence of oil in said conduit will be detected.

5. In a hydraulic oil storage and delivery system, the combination with a storage tank, of an oil delivery conduit and means extending it from said tank, a water conduit also connected to said tank and arranged to surround a portion of said oil delivery conduit, means for supplying displacement water to 85 said water conduit, a riser extending from said water conduit and arranged to collect 90 therein any oil leaking from the oil delivery conduit into the displacement water conduit, and means for indicating the presence of the oil collected in said riser.

6. In a hydraulic oil storage and delivery system, the combination with a storage tank, of an oil delivery conduit and means extending it from said tank, a water conduit also connected to said tank and arranged to surround a portion of said oil delivery conduit, means for supplying displacement water to 100 said water conduit, a water waste pipe connected with the water conduit and comprising a U-shaped pipe the upper bent end 105 of which is above the normal water level, and means for indicating the presence of oil in the portion of said water conduit surrounding said oil delivery conduit comprising a riser carrying a sight device and connected to the water conduit between the 110 tank and waste pipe.

7. In a hydraulic oil storage and delivery system, the combination with a storage tank, of an oil delivery conduit and means extending it from said tank, a water conduit also connected to said tank, a water jacket surrounding said oil delivery conduit and connected to said water conduit, means for supplying displacement water to said water 115 conduit, a riser from said water conduit extending above the normal hydrostatic head of the water and a transparent chamber in said riser for collecting any oil 120 in said water conduit.

8. An oil storage system comprising a tank, a main pipe leading to the lower portion of said tank, a partition plug in the main pipe dividing it into an upper oil fill pipe and a lower water pipe, a laterally ex- 125

tending oil filling pipe connecting with the oil filling pipe above the plug and leading to the upper portion of the tank; an oil delivery pipe concealed within the upper oil fill pipe beginning at a point above the tank, extending down through the plug, past the laterally extending oil fill pipe, and project-

ing through the wall of the main pipe; and a water pipe encasing the oil delivery pipe beginning at and connecting with the main 10 pipe below the plug.

In testimony whereof I affix my signature.

FREDERICK G. FARR.
